ANGELO PERRI, OF HAVERHILL, MASSACHUSETTS, ASSIGNOR, BY MESNE ASSIGNMENTS,
TO UNITED SHOE MACHINERY CORPORATION, OF PATERSON, NEW JERSEY, A COR-
PORATION OF NEW JERSEY.

ASSEMBLING AND PULLING-OVER MACHINE.

1,324,268.

Specification of Letters Patent.

Patented Dec. 9, 1919.

Application filed March 2, 1915, Serial No. 11,596. Renewed February 18, 1918. Serial No. 217,994.

To all whom it may concern:

Be it known that I, ANGELO PERRI, a citizen of the United States, residing at Haverhill, in the county of Essex and State of Massachusetts, have invented certain Improvements in Assembling and Pulling-Over Machines, of which the following description, in connection with the accompanying drawings, is a specification, like reference characters on the drawings indicating like parts in the several figures.

This invention relates in general to machines for use in the manufacture of boots and shoes, and is herein shown as embodied in a machine for use in assembling the parts of boots and shoes on a last and for thereafter subjecting the assembled parts to a pulling-over operation. It should be understood, however, that in its broader aspects and in many of its features the invention is not necessarily limited to machines for performing these particular operations in shoe manufacture.

Heretofore it has been common practice in most shoe factories to assemble the shoe materials, which include a lined upper, a counter and an innersole, on a last in proper relation for the subsequent shoe making operations, either by hand or with the aid of an assembling machine, and to secure the assembled parts by one or more tacks which are driven through the materials and into the last. The last and the assembled shoe are then removed from the jack or support, and subsequently the shoe upper is pulled over, this operation being most commonly performed by a pulling-over machine. This practice not only consumes considerable time, but in the removal of the shoe from the support or jack on which the assembling operation was performed and its transfer to the pulling-over machine there is more or less danger of disarranging the shoe materials on the last and especially at the fore part of the shoe, as the tacks which secure the assembled upper, counter and innersole in position are ordinarily driven into the rear end of the last. It is highly desirable that these parts should be assembled on the last before the shoe is pulled over in the exact relative positions which they are to occupy in the finished shoe, and, when once properly as-

sembled, it is equally important that said parts should be maintained in such relation until they are finally secured together, as the appearance and durability of the shoe are largely dependent thereon.

It is one of the principal objects of the present invention to secure and maintain the exact relation of shoe parts on a last in the interval between different operations on the shoe. To this and other ends, an important feature of the invention resides in a novel construction and arrangement including shoe positioning means which is movable from one position to another to permit the shoe to be presented alternately for the performance of different manufacturing operations. The construction shown as embodying this feature comprises a shoe support or jack which is constructed and arranged to hold a last in a given position while the upper, counter and sole or innersole of a shoe are being assembled thereon, and is movable for carrying the assembled shoe parts into a different position to present said shoe to pulling-over mechanism. The shoe is thus assembled and pulled-over on a single machine, and hence without the necessity of transporting the last and shoe materials after the assembling operation to a different machine, which might mean carrying said parts to a different part of the shoe factory.

In the construction herein shown the shoe support is pivoted to the frame of the machine so as to swing about a center, and is arranged to present the shoe with its sole face upward during the assembling operation, and to move through an arc of approximately 90 degrees to carry the assembled shoe to a position slightly inclined to a vertical plane, where it will be in operative relation to the pulling-over instrumentalities. When in the latter position the top portion of the shoe will be in full view of the operator as he stands in front of the machine so that he can observe the position of the upper and all of its parts, including the tip seam, and will thus be able to detect any incorrect positioning of said parts, and to make such adjustments as are necessary to correct the same.

Another important feature of the invention consists in novel means for retaining the heel end portion of the shoe in correct

relation to the last, the construction shown comprising a heel band or clasp which is carried by the shoe support and is operated automatically to clamp the upper and counter against the rear end portion of the last to hold the shoe parts in assembled relation for the pulling-over operation. As shown, such clamping is made to occur as the assembling jack or shoe support swings from assembling to pulling-over position. The heel band acts to hold the front ends of the counter tightly to the sides of the last, and also to secure the upper and counter firmly to the last while the assembling tacks are being driven, and until the shoe is pulled-over and the upper secured in pulled-over position. The heel band is furthermore automatically opened to release the shoe when the shoe support is returned, subsequently to the pulling-over operation, to the position it originally occupied, so that the pulled-over shoe may be removed and another last with the shoe materials which are to be assembled arranged loosely thereon, may be placed on the support.

Another important feature of the invention is found in the mechanism which drives the tacks for securing the assembled shoe parts at the heel end of the last. In the illustrated embodiment of the invention this mechanism includes two tack-drivers carried by the shoe support, one of said drivers being arranged in position for driving a tack through the upper and counter at the rear end of the last, and the other driver for driving a tack through the upper, the counter flange, and the sole or innersole, at the rear end part of the last bottom, and suitable means for feeding tacks beneath said drivers. Preferably the tack drivers are constructed and arranged to be retracted against the force of their driver-spring by mechanism which is actuated by power derived from the main power shaft of the machine, and are subsequently tripped and drive the tacks through the assembled shoe material, said operations being effected when the operator steps upon the starting treadle after the shoe support is moved to carry the assembled shoe into pulling-over position.

Another feature of importance is found in an improved means for clamping the last firmly to the support, and comprises a bottom rest which, in the construction shown, is spring-pressed, and is arranged to engage the last bottom beneath the heel and in substantial alinement with a spring-pressed jack pin. The bottom rest clamping member has a stem which slides in a rigid part of the shoe support, and the end portion of said stem is arranged to engage a rigid abutment when the shoe support swings the shoe into pulling-over position, thereby forcing said member against the

shoe which is thus clamped firmly at the heel end by said members, and additionally by the heel band.

The upper of the assembled shoe is pulled-over by mechanism comprising, in the preferred embodiment of the invention, three pincers, one being located at the toe end and one upon each side of the fore part of the last. In the construction shown manual means is provided for first causing the pincers to close upon the margin of the shoe upper, and then, by a continued movement to apply to the upper a yielding pull and to strain it to the last, but in its broader aspects the invention is not limited to manual means for operating the pincers. Important features of novelty reside in the pincer operating mechanism, the illustrative construction comprising a hand-operated lever and a novel arrangement of connections with the pincers that enable the operator after inserting the margin of the upper between the jaws of the pincers to cause by a single movement of the hand lever the pincers to seize and then to pull the upper. This may be a preliminary pull of it just a sufficient amount to hold the upper snugly about the last, and in the construction shown is positively limited in extent. This preliminary straining is usually preceded by any adjustments of the upper upon the last that are found to be necessary. The operator then may make another inspection of the upper, and if it has been pulled in proper relation to the last, a second and final pulling strain is applied. In the illustrated construction this second pull is applied through another hand lever and connections with the pincers, said connections being of a character to apply a greater amount of power to the pull than was applied through the first-mentioned lever and permitting a pull of indeterminate extent to be effected. As shown, a continued movement of the second pulling lever by the operator will trip a latch and leave the pincers, and their support, free to move away from the shoe when the pincer jaws have been opened by a subsequent operation of the machine.

Another important feature of the invention is found in an improved means for clamping the shoe at the fore part of the last prior to the release of the upper by the pincers, so as to maintain the upper in its pulled-over position until the tacks which secure it have been driven by the fore-part tackers. In the illustrated embodiment of this feature of the invention this means consists in part of a toe end clasp, and in part of an upper pressing-pad. The toe-end clasp, under the present invention, comprises a band of flexible material, such as sheet steel, having a lining of felt, or other soft material, provided with teeth so as to fric-

tionally engage the upper leather, but without marring the surface thereof. The clasp is preferably connected with yieldingly-actuated arms which hold the clasp normally 5 open or extended. The clasp is supported by a carrier which slides in a guide sustained by the frame of the machine at a distance from the toe end of the shoe, but in alignment therewith. The upper-pressing pad is 10 also supported normally at a distance from the toe end of the shoe. After the final pull has been given to the upper, the operator again steps on the treadle which starts the machine and, through suitable mechanism, 15 the clasp is moved against the toe end of the shoe and is wrapped about the fore part thereof, and the upper-pressing pad is also moved against the upper at the top of the last and the upper is pressed down into the 20 depression found at the rear of the high toe in modern lasts. Immediately following these operations the power-actuated mechanism of the machine effects an opening of the pincer jaws by interrupting the connection 25 between the pincers and the lever through which the jaws were closed, and the pincers are then moved away from the last to provide room for the fore-part tackers.

Still another important feature of the invention 30 is comprised in the mechanism for driving tacks to secure the pulled-over upper in position at the fore part of the shoe, and in the construction and arrangement of parts whereby such mechanism is moved into 35 operative relation to the shoe, is caused to drive tacks, and is finally removed from the shoe following a tack-driving operation. In the illustrated embodiment of the invention 40 this mechanism comprises three tack driving devices, one being arranged for use at the toe-end, and the other two for use at the sides of the shoe to the rear of the toe. These devices are preferably supported by 45 the same carrier that supports the toe end clasp so as to be moved into and out of operative relation to the shoe by the same power-operated mechanism as the clasp. It is a feature of this part of the invention, however, that the said carrier is made in 50 two relatively movable parts that are yieldingly connected, one part supporting the toe clasp and the other part supporting the tackers. The construction and arrangement 55 of said parts is such that the clasp is first moved up to the shoe and engages it, in advance of the tackers, then the pincers are opened to release the upper and are immediately moved away from the shoe to make 60 room for the tackers, and the machine is again brought to rest before the tackers have been moved completely into operative relation to the shoe. These tackers, besides being movable as an entirety toward and from the shoe, are in the illustrated embodiment 65 of the invention capable of additional move-

ments, the two side tackers being foldable in against the sides of the shoe, and all three of the tackers turning through an arc of ninety degrees so as to ride over the edge of the fore part of the shoe and slide in upon 70 the margin of the shoe bottom. The tackers have at their bases rounded corners which during these movements press the upper against the edge of the innersole, and force it snugly into the corner or angle at the 75 junction of the lip and the feathered edge. The described movements of the tackers serve to smooth out the wrinkles in the margin of the upper and to hold it firmly in the position where it is to be fastened until the 80 tacks are driven. The tacks are fed in position below the drivers by any preferred tack feeding devices, and are retained in such position until driven into the shoe. The tack-driving blow is delivered to the three 85 drivers simultaneously while they are grouped about the fore part of a shoe by a spring-actuated lever, which is pivoted to the tack-driver carrier, and has connection with the frame of the machine so as to be 90 moved away from the tackers to store power in its spring and thus be set in condition for operation, automatically, as the carrier is moved away from a shoe, being retained in such position by a suitable latch. When the 95 tackers are moved in over the edge of the shoe a continued operation of the machine causes movement of the latch to trip the lever and thereby effect driving of tacks to secure the pulled upper to the innersole. 100 Following this operation the power-actuated mechanism returns the fore-part tackers, the toe-end clasp, and the upper pressing pad to their formerly-described positions in which they are removed from the end of the shoe. 105 Such return movement of the tackers serves to re-set the driver-actuating lever, which is then retained in set condition by its latch.

These, and other features of the invention, including important details of construction 110 and combinations of parts, will be hereinafter more particularly described and claimed.

In the drawings:

Figure 1 shows, in side elevation, a machine embodying the present invention, and a shoe in position to be operated upon thereby;

Fig. 2 is a perspective view, somewhat enlarged, of the pincers and sole rest, together 120 with the forepart of an assembled shoe which is to be pulled over;

Fig. 3 is an enlarged detail view, in side elevation, showing the shoe parts in assembled position on a last, the heel clasp, and the devices for driving tacks for securing the shoe materials at the heel;

Fig. 4 is a perspective view of the toe clasp and fore-part tackers;

Fig. 5 is a detail view, partly in longitu-

dinal section, of the parts that appear in Fig. 4, and showing also the lever for actuating the drivers for the fore-part tackers;

Fig. 6 shows the toe clasp, and

5 Fig. 7 is a perspective view of the fore-part tackers in operative relation to the fore-part of a shoe.

The machine frame comprises a base A, and a head B which extends upward from 10 the base and supports the mechanism for use in assembling the shoe parts and securing them at the heel end of a last, and for pulling-over the assembled shoe parts and securing them in pulled-over position.

15 The base A supports in suitable bearings a shaft 99 carrying a loose pulley 100, to which may be applied a belt for receiving power from a suitable source. The pulley 100 is preferably arranged to be connected 20 to the shaft 99 by a clutch, and the movable member 103 of the clutch carries a pin which is adapted to engage a wedge 102 connected to an eccentric pin, or the equivalent, at one end of a rod 104, which is rotatable in bearings carried by the base A, and carries at its other end a treadle 12. When the treadle is depressed the wedge will be withdrawn, thereby releasing the movable clutch member which will be spring-pressed into engagement with the loose pulley and clutch it to the shaft 99. When the treadle is released the wedge will be caused by a spring (not shown) to reengage the pin carried by the movable clutch member when the shaft 30 has completed one rotation and will withdraw said member from engagement with the loose pulley, and the motion of the shaft will then be arrested.

The inner end of the shaft 99 carries a 40 beveled gear 106 which meshes with a beveled gear 108. The latter has three times the number of teeth of the gear 106, and is fast to one end of a shaft 110 which rotates in bearings carried by the frame base. The 45 shaft 110 has fast to its other end a beveled gear 112 meshing with a beveled gear 114, carried by a shaft 116, that is also rotatably supported in bearings in the frame base. A cam 118 is fast to the shaft 116, and a rod 50 120, which reciprocates in a guide supported by the frame, carries at one end a cam roll α that engages the cam 118, and at its other end is connected by a ball and socket joint with one arm of a bell-crank 122 that is fulcrumed to a bracket 21 projecting rigidly from the frame head B. The other arm of the bell-crank has pivotal connection with one end of a link 8 whose opposite end portion has a slot 8 $\circ$ which receives a pin 9 projecting from a transverse bar 11 which carries lugs for pivotally supporting the right-angular shaped pawls 15, 15, for setting and releasing the tack drivers for use at the heel end of the shoe. The bar 11 is rigidly attached to a slide 10 which is guided in its

movements by bars 10 a , 10 a , projecting rigidly from a block Z. This block is secured firmly to an arm 7 which has a pivotal connection 3 with a cam-shaped extension 21 a of the bracket 21. The arm 7 is arranged 70 to swing about the cam-shaped extension, and carries guiding lugs f , g , for a pin 1 which slides in perforations in the lugs, and a spring 4, confined between an abutment on the pin and the lug g serves to yieldingly hold the inner reduced end of the pin in the jack pin hole of the last which carries the shoe parts. The thrust of the pin 1 is opposed by a heel rest 130 whose stem slides in a hole through the block Z, and carries a button 133 at its outer end, and a spring 131 surrounds the stem of the heel rest and is confined between the button 133 and the inner face of the block.

The bracket 21 carries an internally 85 threaded lug which receives an adjustable stop screw 132, arranged in position to engage the button 133 when the arm 7, constituting the jack, is swung from shoe-assembling position as shown in Fig. 3, to 90 pulling-over position, as shown in Fig. 1, whereupon the springs 131 and 4, being compressed, will re-act through the jack pin and heel rest to clamp the shoe yieldingly in position for the operation of the pulling- 95 over devices.

The driver 13, for driving the tack through the assembled shoe materials on the last bottom near the rear end of the sole,—which materials include the innersole, the 100 lined upper and the flange of the counter,—slides through a perforation in the block Z and has a driver bar 13 b which passes loosely through a guide-opening in the transverse bar 11. This driver bar carries 105 a pin 13 c which is acted upon by one end of a spring 13 a whose function is to force the two drivers toward the shoe bottom. The driver 14 for the tack that is driven through the assembled shoe materials at the 110 back of the heel is arranged at right angles to the driver 13, and has connection with one arm of a bell-crank 140 which is fulcrumed to the block Z and has its other end pivoted to the driver bar 14 a . This driver bar has 115 a pin 14 c which is acted upon by the other end of the spring 13 a . The upper end portions of the driver bars have inwardly projecting lugs e that are engaged by the outer ends of the pawls 15 which are acted on by 120 springs confined between the inner ends of these pawls and the bar 11. When the bar 11 is raised the driver bars will be lifted, thereby putting the spring 13 a under tension. A continued movement of the bar 11 125 causes the inner ends of the pawls to engage the pins d , carried by the guides 10 a , thereby tripping the pawls and permitting the spring 13 a to actuate the drivers 13 and 14, and drive the two tacks that hold the assembled 130

shoe materials in position at the heel end of the last. The tacks, preferably in strip form, are fed successively below the drivers 13, 14, prior to each driving operation, by 5 any suitable automatic tack-feeding mechanism.

The flexible heel band 5, which clamps the shoe materials firmly about the heel end of the last after the assembling operation 10 and prior to the pulling-over of the shoe, is preferably cut away at its rear central portion, in line with the tack driver 14 to provide for driving the tack through the upper and counter at the rear of the heel 15 without penetrating the band. An important function of this band is to press the counter, and especially its end portions, firmly against the heel end of the last, and to hold the counter and the upper thus 20 pressed while the tacks are being driven by the drivers 13 and 14 so as to prevent displacement of these shoe parts until they are secured in position by the tacks. The heel band is pivotally supported near its outer 25 ends upon the curved arms 6 of a bell-crank which is fulcrumed by a pin 6^a to the block Z. The bell-crank has an arm 6^b which carries a cam roll 50^a engaging the cam-shaped extension 21^a of the bracket 21. A 30 spring 6^c, which may be coiled around the pivot pin 6^a, acts against the arms 6 of the bell-crank, and serves to force the ends of the heel band forward to wrap the band about the heel end of the shoe when the arm 35 7 is swung about its pivot from the position shown in Fig. 3 to that shown in Fig. 1, the cam roll 50^a passing from the high to the low part of the cam 21^a during this movement of the arm 7. When the arm is 40 swung reversely to carry the shoe from the position shown in Fig. 1 to that shown in Fig. 3, following a pulling-over operation, the cam roll passes from the low to the high portion of the cam and the arms 6 of the bell-crank are moved rearwardly, thereby 45 opening the heel band and releasing the shoe.

A rest 16, having spaced feet to engage the bottom of the sole at the fore-part of a shoe, has a threaded stem 160 which slides 50 in a hole in a plate 162 and is held from turning therein by a pin 16^a and groove 16^b. A winged nut 161 is threaded to the stem and bears against the plate. The plate 162 is provided with a slot, and a clamping bolt 55 163 passes through the slot and has threaded engagement with the bracket 21. The rest 16 is adjustable toward and from the shoe bottom by means of the winged nut 161, and is adjustable in a plane substantially parallel with the shoe bottom by unscrewing the clamping bolt 163 and moving the plate in the direction of its slot.

The pincers for pulling-over the shoe are preferably three in number, one being 60 located at the center of the toe end of the

shoe, and one on each side and substantially at the end of the toe tip seam. The pincer shanks 170, 170^a, 170^b terminate in rigid jaws, and a coöperating movable jaw 17 is pivotally connected to each rigid pincer jaw, the gripping faces of the jaws being preferably roughened to increase their frictional hold upon the stock. A rod 171 is connected at one end by a ball and socket joint with each movable pincer jaw and each rod extends through a hole in a boss formed on its pincer shank, and is thereby guided in its movements. Spiral springs 172, which surround the rods 171, are compressed between pins on the rods and the guiding bosses with sufficient tension to force the rods rearwardly, when not prevented from doing so, thus holding the pincer jaws open. The shanks 170^a and 170^b of the side pincers are connected with each other by a bridge 18 which has near its ends slots, and pins or screws 20 pass through the slots and are secured to the pincer shanks, whereby the side pincers may be adjusted different distances apart for shoes of varying widths. An adjusting screw 174 has its inner end connected centrally to the bridge 18 with capacity for turning movement, and is externally threaded to engage a thread in a nut 174^a which is trunnioned in the walls of a slot through the pincer shank 170. The outer end of the screw 174 is provided with a hand wheel, as shown, which may be manipulated for turning the screw in either direction to thereby position the toe-end grippers different distances from the side grippers for shoes of different sizes.

The pincer shanks are connected pivotally at their rear ends with sleeves 28, 28^a, 28^b, the central sleeve 28 being connected with the shank of the toe-end pincer, while the sleeves 28^a and 28^b are, respectively, connected with the shank of each side pincer. The sleeve 28 is supported for sliding movements upon a rod 35 to which the sleeve is connected by a slot 240, and a pin 241 on the rod, for limiting the extent of such movements, and the sleeves 28^a and 28^b are similarly supported upon rods 135^a and 135^b, and are likewise limited in their sliding movements thereon by slot and pin connections as shown in Fig. 2. The rods 35, 135^a, 135^b are rigidly connected with each other at their forward ends by a bar 39, and springs 136 surround the rods and are confined between the bar and the sleeves 28, 28^a and 28^b.

The rods 171 for closing the pincer jaws are connected at their rear ends by ball and socket joints with bell-crank 176, 176^a, 176^b, whose rear arms are acted upon by cams 22, 22^a, 22^b, pivotally supported upon the rods 35, 135^a, and 135^b. The cam 22 has its outer free end connected by a pin with a slot 181 in one end of a rod 178 and a spring N extends from the end of this rod to a pin car-

130

- ried by the bridge 39. A block 179 is secured to the rod 178 and is provided with perforations, one on each side of the rod 178, to receive two short rods 178^a, 178^b.
- 5 The inner ends of these rods are slotted at 181 to receive pins on the outer, free ends of the cams 22^a and 22^b. Spiral springs 180 surround the rods 178^a, 178^b, and are confined between nuts threaded to the outer 10 ends of these rods and the block 179, thus providing yielding connections between the rod 178, and the rods 178^a and 178^b.
- The rear end of the rod 178 is pivoted to one arm of a lever 37, which is fulcrumed to 15 the machine frame and has its other arm formed as a segmental gear 371, as shown. This gear meshes with a segmental gear 360, formed on one arm of a lever 36, which is also fulcrumed to the frame of the machine.
- 20 The other arm of the lever is formed as a segment 361, having notches therein to receive a tooth 27 which is carried by a short lever 27^a, pivoted to the short arm of the lever 210, and connected at its free end by a 25 rod 27^b to a pawl-controller 211, which is pivoted to the long arm of the lever 210 near the end thereof. The lever 210 is fulcrumed to the same shaft as the lever 36, and has a pawl 26 which engages the teeth of a rack 260, supported from the frame. This pawl is connected by a rod with the controller 211 upon the opposite side of the pivot from the point of connection of the rod 27^b with the controller. The lever 210 may be set at a 30 convenient height for operation by placing the tooth 27 in the desired notch in segment 361. The lever 210 is manually releasable from its rack by withdrawing the pawl 26 from the rack 260, and may be depressed 35 to effect rearward movement of the rods 178, 178^a and 178^b, which will thereby cause the cams 22, 22^a and 22^b to rock the bell-cranks 176, 176^a and 176^b, and project the rods 171 forward, compressing the springs 172 and 40 closing the pincer jaws. A continued downward movement of the lever 210 will, by exerting further strain on the rod 178, move the three pincers and the entire pincer-carrying frame bodily in a direction to stretch 45 the upper, and the lever will be retained in position with the upper held under tension by the engagement of the pawl 26 with the rack 260. A balance spring 101 extends from the lever 210 to the fulcrum of the bell-crank 122, or other fixed point, and assists in holding the pawl 26 in engagement with the rack when an upper is under tension.
- The pincer rod 35 extends rearwardly and is externally threaded to engage the internal threads of a nut 236, carried rigidly by a sleeve 34 to the opposite end of which is secured a pinion 45. The sleeve is rotarily supported in a tubular bearing 34^a carried rigidly by a box or casing 33. The casing 50 55 60 65 70 75 80 85 90 95 100 105 110 115 120 125 130

movements in parallelism with the pincer rod 35, upon a plate 141 that extends laterally from a bar 138 which is mounted to slide in bearings in the frame and has teeth which mesh with a pinion 139. This pinion is fast to a shaft that turns in bearings in the frame and has a hand-lever 340 by which the pinion may be turned for raising or lowering the casing 33 carrying the pincers. These adjustments provide for moving the three pincers simultaneously to locate the pincers in proper position for operation upon shoes of different lengths.

A segmental rack 44 meshes with the pinion 45, and is provided with a rigid arm 45^a which is pivoted at 45^b to a lug extending from the box or casing 33. The rack 44 is reciprocated by a lever 43, fulcrumed at 84 to the frame head, and connected by a link 85 to the rack. The handle end of this lever 85 extends toward the front of the machine and is in position for convenient manipulation by the operator. After the lever 210 has been depressed to cause the pincers to seize the upper and to strain it preliminarily to the last, a further pulling of the upper may be effected by depressing the lever 43 which causes the rack 44 to rotate the pinion 45, sleeve 34, and nut 236, thereby moving the pincer rod 35 rearwardly and applying through the springs 136 a yielding strain to the upper. A lever 46, fulcrumed at 45^b to the casing 33, has its forwardly-extending arm connected by a link with a latch 47, which is pivoted to the casing and has near one end a shoulder to engage the forward edge of the plate 141 and has also a tooth oppositely directed with respect to said shoulder to engage the wall of a recess in the plate. The rearwardly-extending arm of the lever 46 is connected with the arm 45^a of the rack 44 through a spring 86 so as to be raised to lift the latch 47 out of engagement with the plate 141 when the rack is moved upwardly to impart the final upper-straining movement to the pincers. The construction and arrangement of the described parts are such that during the first portion of the upward movement of the rack the nut 236 will be rotated and thus impart a final pull to the pincers while the latch 47 holds the casing 33 against movement in either direction, and the spring 86 will yield and thus delay the tripping of the latch. Upon a continuation of the upward movement of the rack, however, the spring will be compressed sufficiently to trip the latch, thus releasing the frame 33 so that the frame and pincers will be free to move rearwardly and away from the shoe when the pincers have been opened to release their grip upon the upper, as will be more fully explained hereinafter.

Just before the pincers release their grip upon the pulled upper an upper-pressing

pad 90 is, through power-operated instrumentalities, caused to move down and engage the upper at a point over the fore part, at or near the tip line, and to press the shoe 5 materials firmly against the last and into the depression which is found back of the toe in high-toed shoes. This pad has a stem that slides in a bearing in an arm 91, and a spring 90^a, located between an enlargement 10 on the stem and the arm 91, provides for a yielding pressure of the pad against the shoe. The arm 91 is pivoted to a rigid part 15 of the frame, and a link 89 and sliding rod 89^a connect the arm with a cam roll 92 that runs in a cam groove in the upper face of a cam 196, which is supported for rotation in bearings on the frame head. The cam has a geared connection with a gear 94, the ratio of these gears being one to one. The 20 gear 94 is fast to a shaft 95, rotating in bearings carried by the frame, and having secured to its lower end a gear 96 which meshes with and is driven by a gear 97, having the same number of teeth as the gear 25 96, and which is secured to the shaft 110 heretofore referred to.

The shoe materials about the toe end of the last are held in position, following the pulling-over operation, by a toe clasp, which 30 is power-operated, and the pulled upper is secured to the last by tacks that are driven through the upper materials and the margin of the innersole while the upper is being held to the end portion of the last by the 35 toe clasp.

Referring more particularly to Figs. 1, and 4 to 7, inclusive, an arm 42, rigid with the frame head B, projects downwardly therefrom substantially in line with the shoe 40 when the shoe is supported in position to be pulled-over. This arm has a guideway therein which receives the sliding carrier 41 to which are pivoted at 182 two outwardly curved arms 50, whose outer ends are connected with the end portions of the toe clasp 45 40. The toe clasp, as herein shown, is composed of a flexible band of sheet steel, or other suitable material, provided with a felt, rubber, or other soft lining having V-shaped projections or teeth 40^a that will readily conform to the curvature of the toe-end portion of a last and engage the upper leather frictionally in a manner to firmly press it about the end of the last, but without 50 injuring or marring its surface. The hubs of the arms 50 are provided with inwardly projecting lugs 183 which engage a spring-pressed plunger 184, sliding in a recess at the lower end of the carrier 41, and 55 which acts to yieldingly force the arms 50 outward and thereby hold the clasp in open or extended condition. When the clasp is forced against the toe end of a shoe the pressure on the center of the clasp will draw 60 the outer ends of the arms 50 inward, there-

by forcing the plunger 184 into its recess and compressing the spring 184^a so that the clasp will be wrapped about the toe of the shoe against a yielding resistance.

The toe tackers are supported from a carrier member 41^a that is movably connected with the toe-clasp carrier 41 by a rod 185 the lower end of which is secured to the bottom of a recess in the carrier 41, and the upper end is threaded and passes through a 70 perforation in a lug extending from the carrier member 41^a, and a nut is applied to the threaded end of the rod above the lug. A spring 185^a surrounds the rod 185 and is confined between the lug and the bottom of the 75 recess in carrier 41. The two members of the carrier are thus connected through the spring and rod for relative sliding movements, the spring yielding during such movements and exerting a tendency to return the carrier members to the relative 80 positions in which they are shown in Fig. 5.

The tack drivers 186, 186 and 189 for driving the tacks at the end of the toe and upon opposite sides of the shoe near the toe 90 end, are carried by rods mounted for sliding movements in tubular extensions of the frames 187, and spiral springs 186^a, 186^a, 189^a, confined between heads on the rods and the tubular bearings, return the drivers to 95 raised position following each tack-driving operation. The base of each tacker frame is rounded off slightly at its lower front edge 187^x for pressing the margin of the upper snugly into the angle formed by the lip and 100 feather edge of an innersole for a welt shoe, and a flange 187^y extends angularly from the lower face of the tacker base, to the rear of its rounded edge, and serves to press the upper firmly against the outer edge of the 105 innersole.

The fore-part tackers are provided with tack pockets 80 arranged with forwardly-inclined front walls and mounted upon slides 82 that have driver openings 83 there-through, and are operated by springs 83^a. The tacks are supplied to the tack pockets 80 from a hopper 400 through tubes 401, the hopper being provided with any appropriate tack-feeding mechanism, such for example 110 as that disclosed in U. S. Letters Patent No. 663,777, dated December 11, 1900, which automatically feeds a tack to each tube for delivery to its tack pocket when the tackers are in tack-receiving position, as shown in 115 Figs. 4 and 5. In the illustrated embodiment of the invention, there are two tack drivers and two tack tubes for each side tacker, and a single tack driver and tack tube for the toe-end tacker. Each tack, 120 when it is deposited in a tack pocket, gravitates into a driver passage 190 below the pocket where it is retained by a spring or equivalent device, until it is driven into 125 the shoe.

The toe-end tacker and the side tackers are hinged to the carrier 41^a by a hinge pin 56 for enabling the tackers to turn through an angle of substantially ninety degrees in moving from tack-receiving to tack-driving position, and the side tackers are connected with the toe-end tacker by hinges 191 having their axes at right angles to the pin 56 to permit the side tackers to fold in against the sides of the shoe, as shown in Fig. 7. The support for the toe end tacker has a forwardly extending cam member 55 provided with an angular slot which receives a pin 54 projecting rigidly from the side of the arm 42, the shape of the slot being such as to cause the tackers to move from the position shown in Fig. 4 to that shown in Fig. 7 when the carrier 41 is depressed, and to return the tackers to the former of these positions when the carrier is raised.

The side tackers are rigidly sustained upon rods 188 whose inner ends are fast to the movable leaves of the hinges 191, connecting the side tackers with the toe end tacker. Sleeves 58, surrounding the rods 188 and rotatable thereon, are provided with lugs which are pivotally connected with links 59, the links being in turn connected by universal joints with a cross bar 57 that extends through and is guided in slots in the sides of the carrier 41^a, and is pivoted to a rod 60. A spiral spring 192, which is stiffer than the spring 185^a heretofore described, is located below the cross bar in a recess in the carrier 41^a and acts to yieldingly transmit downward movement from the rod 60 to the carrier members 41 and 41^a.

The rod 60, preferably made in two parts connected by an adjustable turn-buckle 60^a, is pivotally connected at its upper end to one arm of a lever 193, which is fulcrumed to the frame head and has its other arm loosely connected to a rod 194 which reciprocates in a guide block 195. This rod carries a cam roll 51^a that engages a cam groove 51 in the cam 196. A link 198 connects the rod with a plate 200, pivoted to the same shaft as the toothed lever 36 and having a cam face which engages the tooth 27 and is arranged to force it out of locking engagement with the toothed segment 361 when the link is raised. The link is made in two parts connected by a turnbuckle 202, through which the timing of the automatic pincer release, toe-clasp closing, and fore-part tacker actuating mechanism may be adjusted.

The fore-part tack drivers are actuated by a lever 72 which is fulcrumed to a pin 72^a on an extension of the member 41^a, and has a driver spring 73 coiled about the fulcrum pin, and with its free end bearing against another pin on the long arm of the lever. The lever 72 has a head 72^b, of sufficient area to engage simultaneously the ends of the three driver rods when the same

are grouped in driving position as shown in Fig. 7, and the short arm 78 of the lever has connection with one end of a link 74 whose other end has a slot 75 which slides along a pin fixed to the frame head.

The carrier member 41^a supports a sliding spring-pressed latch 71 having a beveled end, and the driver-lever is provided with an abutment 710 having a surface which engages the lower face of the latch and retains the lever in position for driving, and a rounded or beveled face below the engaging surface for pushing the latch rearwardly when the lever is being set, or put in condition for action. The rod 60 passes through an aperture in the latch, and carries a wedge 70 which is threaded to the rod for adjustment and is adapted to engage a beveled rear wall of the aperture to cause withdrawal of the latch for tripping the driver lever when the rod is depressed.

The cam groove 51 comprises a straight portion which is occupied by the cam roll when the parts are as shown in Fig. 1, and a raised portion into which the roll passes to effect the automatic pincer release and also the depression of the toe clasp and the toe tackers.

In the use of the machine, the usual shoe materials, including an upper, lining, counter-stiffener and innersole, are placed loosely upon a last, and with the arm 7 turned down into the position as shown in Fig. 3, the shoe is placed in the position shown with the spindle 1 in the jack pin hole of the last and the rest 130 engaging the shoe bottom. The operator then assembles the several shoe parts on the last in the positions that they are to assume in the finished shoe. The arm 7 and parts carried thereby, including the pin 1 and sole rest 130 with the shoe clamped therebetween, the block Z and supported parts, are then swung about the pivot 3, from the position shown in Fig. 3 to that shown in Fig. 1, the pin 9 also swinging around pivot 3, and in doing so it is located near the right hand end of slot 8^a. In this movement the cam roll 50^a moves from the high to the low part of the cam 21^a, permitting the spring 6^a to close the heel band about the heel end of the shoe, the button 133 meets the end of screw 132 thus compressing spring 131 and clamping the shoe between the jack pin and heel rest, and the fore part of the sole meets the rest 16 which arrests the shoe, and determines its position in the machine. The shoe is now presented to the operator in substantially upright position, with its toe pointed upward at a slight rearward inclination so that as he stands in a normal attitude in front of the machine the operator may have a full view of the top of the shoe, and can readily observe if the lines of the upper are in proper relation to the lines of the 130

last. Having determined that the shoe parts are assembled right, the operator steps on the treadle, thereby clutching the loose pulley to the shaft 99, which makes one 5 complete rotation and stops. Prior to starting the machine, the cam roll X rested upon the low part of the cam 118, and the bell-crank 122 and link 8 were held in a forward position. The complete rotation of shaft 99 10 effects but one-third of a rotation of the shaft 110 and of shaft 116 with its cam, the high point of which will meet the roll X and elevate rod 120, thereby swinging the long arm of bell-crank 122 and the link 15 8 rearwardly until the end of slot 8^a engages the pin 9 and pulls the bar 11 in the same direction, which moves pawls 15 until their ends engage and lift the drivers 13, 14 thereby putting the spring 13^a under tension. 20 Continued movement of the pawls will cause their rear ends to engage the pins d, and trip the drivers which will then drive the two assembling tacks into the shoe materials at the heel end of the last. Before 25 the described machine parts are brought to rest the cam 118 will rotate sufficiently to permit the roll X to pass again onto the low part of the cam, thus permitting the spring 122^a to move the bell crank 122 and 30 bar 8 forwardly until the slot 8^a is in such position that the pin 9 will engage the left-hand end of the slot, so as to shift the bar 11 to its inner position when the jack is again swung into the position shown in 35 Fig. 3. While the mechanism for driving the assembling tacks is operating, one-third of a rotation will be imparted to the cam 196, but as the roll 51^a occupies the straight, or low portion of the groove 51 at this time 40 the lever 193 carrying the toe clasp and fore part tackers will not be moved from its elevated position, as shown in Fig. 1.

The assembling operation having been completed, the operator inserts the margin 45 of the upper, at the end of the toe and on both sides of the fore-part, between the open jaws of the pincers. He then depresses the lever 210, which closes the pincer jaws upon the upper, and a continued depression of 50 the lever will move the rod 35 and the rod or casing 33 rearwardly until latch 47 engages the plate 141, such movement transmitting to the pincers an updraw. The pincers may then be retained in position to 55 hold the upper under tension by the engagement of the pawl 26 with the rack 160. Opportunity is now afforded the operator for further inspection of the shoe and, if he finds that the upper has not been pulled 60 properly with respect to the lines of the last, by releasing the lever and slightly raising its forward end the pincer jaws will be opened and the upper may be adjusted properly therein, and the lever again depressed to close the jaws and updraw the 65 upper. The operator then grasps the lever 43 and depresses it, thereby raising the segment 44 and, through the gear 45, sleeve 34 and nut 236, effecting a rearward movement of the rod 35 and bridge 39, thereby compressing the three springs 136, and applying additional tension to the upper. This tension is applied yieldingly through each pincer independently of the other pincers. Continued downward movement of the lever 70 43 will trip the catch 47 and thus leave the casing 33, and pincers connected therewith, free to move rearwardly and away from the shoe a sufficient distance to permit the tackers to move into position. While the 75 pincers retain their hold on the upper, however, the tension of the strained upper prevents the pincers from moving away from the shoe.

The operator then steps on the treadle again 80 and rotation is imparted to the power shaft which effects movement of the cam 196 a further distance and sufficient to cause the cam roll 51^a to enter the high part of the groove 51 and raise the rod 194 far enough 90 to depress the toe-end clasp and wrap it about the toe end of the shoe, and also to move the pad 90 in position against the upper part of the shoe, rearward of the toe. The same movement of the rod 194 causes 95 cam 200 to force tooth 27 out of the segment 361, thereby releasing the lever 37, and permitting the spring N to move the rods 178, 178^a and 178^b forward, the ends of slots 181 then engaging the pins connected with the 100 pincer-closing cams and turning these cams in a direction to permit the springs 172 to open the pincer jaws. The pincers will then be forcibly carried by the springs 136 away from the shoe until the ends of the slots 240 105 engage the pins 241, and the momentum thus imparted to the pincer system will carry the rod 35 and casing 33, and its attached parts, including the pincers rearward far enough 110 to leave ample space between the pincers and the shoe for the accommodation of the fore-part tackers. The machine will then be brought to rest a second time by the one-revolution clutch, the cam roll 51^a having progressed part way along the high part of 115 the cam groove.

The operator then steps on the starting treadle a third time, and further rotation of the cam 196 is effected to cause the roll to enter the final portion of the high part 120 of the cam groove, thus depressing the rod 60 a further distance. This movement folds the side tackers about the sides of the fore-part of the shoe and turns the side and end tackers in upon the sole, the corners 125 187^x of the tackers smoothing out any wrinkles in the upper and pressing it snugly into the angle between the feather edge and lip of the innersole, and the flange 187^y pressing the upper margin firmly against 130

the edge of the innersole. A continued movement of the rod trips the lever 72, which is driven by its spring against the drivers and thus effects the driving of the 5 tacks to secure the pulled-over upper in position. This completes the operation of assembling and pulling-over the shoe, and the machine is thereafter brought to rest. Before the movement of the power shaft 10 stops, however, the upper cam groove in the cam 196 raises the arm 91 and removes the pad 90 from the top of the shoe, and the cam roll 51^a passes into the low portion of the groove 51, thus effecting upward movement of the toe clasp and the toe-end tackers, and restoring these parts to the positions formerly occupied by them and where they will be in readiness for operation upon another shoe. At the same time the cam 15 200 is restored to its original position, permitting the tooth 27 to reengage the toothed segment 361 and to lock the lever 210 to the lever 36, thus reestablishing an operative connection between the pincers and their 25 closing and pulling lever. The lever 210 will next be manipulated to move the pincers and the supporting casing 33 toward their initial position, and the lever 43 will then be raised for moving forward the pincer 30 35 rod 35 carrying the pincers, and for depressing the latch 47 into position to coöperate with the plate 141 in the manner hereinbefore described when another shoe is operated upon. The operator then swings the 35 shoe support into the position shown in Fig. 3 which unclasps the heel band from the counter, the shoe is removed, and the machine is in readiness for another operation.

Having described my invention, what 40 I claim as new and desire to secure by Letters Patent of the United States is:

1. The combination with a support arranged to occupy one position while the parts of a shoe are being assembled on a 45 last, and movable to a different position to present the shoe to pulling-over means, of pulling-over means arranged for operation on the shoe while it is in the last-named position.

2. The combination with a shoe support 50 arranged to be located in one position while the shoe parts are being assembled on a last, and movable about a center into a different position to locate the shoe properly for the 55 pulling-over operation, of means for pulling-over the shoe while it is in the last-named position.

3. The combination with a support for holding a shoe with its sole face uppermost 60 during the assembling operation, and movable to present the shoe in position with the top of the forepart of the upper toward the operator, of means for pulling-over the shoe while it occupies the last-named position.

4. The combination with means to sup-

port a shoe in one position while its parts are being assembled on a last, of a heel band, and means to close said band about the heel end of the shoe as said support is moved into a different position.

5. The combination with a support for holding a shoe in one position while its parts are being assembled on a last, of means for driving a tack through the materials at the heel end of the shoe arranged to be operated when said support has been moved into 75 a different position.

6. The combination with a support for holding shoe parts in position to be assembled on a last and movable into another position to permit the shoe to be pulled-over, of tack-driving means, and mechanism for actuating said means when the shoe is in the last-named position.

7. The combination with a support movable to carry a shoe from assembling to pulling-over position, of a heel band carried by said support, and means to close the band about the heel end of a shoe when said support is moved into pulling-over position, 90 and to open the band and release the shoe when said support is returned to assembling position.

8. The combination with a shoe support movable to carry a shoe from assembling 95 position to pulling-over position, of tack drivers carried by said support arranged to drive one tack through the materials at the back of the heel and another tack through the materials near the heel end of the sole, 100 and power-operated means to retract and trip said drivers when the assembled shoe has been carried into pulling-over position.

9. The combination with a shoe support movable about a fixed axis to carry a shoe 105 from a position in which the shoe parts are assembled to a position in which the shoe is pulled over, of pulling-over means located in operative relation to the shoe when it is in the last-named position; and shoe clamping 110 means which becomes operative when said support is moved into said last-named position.

10. The combination with a shoe support movable to carry a shoe from a position in 115 which the parts are assembled to a position in which the shoe is pulled over, of oppositely arranged members for clamping the shoe between them, and an abutment arranged to engage one of said members when the shoe is moved into the last-named position.

11. The combination with a shoe support movable to carry a shoe from a position in 125 which the parts are assembled to a position in which the shoe is pulled-over, of a spring-pressed jack pin for engaging the last, a yielding rest for engaging the shoe bottom, and an abutment arranged to engage said rest when the shoe is moved into the last- 130

named position to effect clamping of the shoe between said rest and jack pin.

12. The combination with a shoe support movable to carry a shoe from a position in which the parts are assembled to a position in which the shoe is pulled-over, of a heel band, oppositely disposed clamping devices for engaging the shoe, and means actuated by movement of said support for causing said band and clamping devices to clamp the shoe when it is moved into the last-named position, and to unclamp the shoe when it is returned to the first-named position.

13. The combination with a frame, of a shoe support pivotally sustained by the frame, a heel band, a lever connected with the ends of said heel band, yielding means arranged to act on said lever to clamp said band about the counter of a shoe when said support is moved to carry the shoe into a position with its toe pointing upward and a cam arranged to act on an arm of said lever in opposition to said spring for unclamping the band when said support is moved to position the shoe with its sole face upward.

14. In a machine of the class described, the combination with a frame, of a shoe support sustained by said frame for swinging movements to carry a shoe from a position with its sole face upward to a position slightly inclined to a vertical plane, a sole rest arranged to engage the shoe and arrest its movement when it reaches the last-named position, and means for pulling-over the shoe while the sole is in engagement with said rest.

15. In a machine of the class described, the combination with a frame, of a shoe support sustained by the frame for swinging movements to carry a shoe from a position with its sole face upward to a position slightly inclined to a vertical plane, a sole rest for determining the last-named position, means permitting adjustment of said rest in a direction substantially perpendicular to the plane of the sole, and means for pulling-over the shoe while the sole is in engagement with the rest.

16. In a machine of the class described, the combination with a frame, of a shoe support sustained by the frame for swinging movements to carry a shoe from a position with its sole face upward to a position slightly inclined to a vertical plane, a sole rest for determining the last-named position, means permitting adjustment of said rest in a direction substantially parallel with the sole face, and means for pulling-over the shoe while the sole is in engagement with the rest.

17. In a machine of the class described, the combination with a frame, of a shoe support sustained by the frame for swinging

movements to carry a shoe from a position with its sole face upward to a position slightly inclined to a vertical plane, a sole rest for determining the last-named position, means permitting adjustments of said rest in directions substantially perpendicular to the sole and also substantially parallel therewith, and means for pulling-over the shoe while the sole is in engagement with the rest.

75

18. A machine of the class described having, in combination, pincers arranged to engage an upper, manual means to cause said pincers to seize and pull the upper, and power-operated means to cause said pincers to release their grip on the upper.

19. A machine of the class described having, in combination, pincers for engaging an upper, manually-operable means including a lever and connections for closing the pincers upon the upper and for moving the pincers to pull the upper to the last, and power-operated means for interrupting the connection between said lever and pincers to release the upper.

90

20. A machine of the class described having, in combination, pincers for engaging an upper, a manually operable lever and connections for closing the pincers upon the upper and for moving said pincers to preliminarily strain the upper to the last, and a second lever and connections with the pincers for subjecting the upper to additional strain.

95

21. A machine of the class described having, in combination, pincers for engaging an upper, a support therefor, a manually-operable lever and connections for closing the pincers' jaws upon the upper and for moving said pincers to preliminarily strain the upper to the last, a second lever and connections with the pincers for subjecting the upper to additional strain, and means, which is rendered operative by a continued movement of the last-named lever, to permit the pincer support and pincers to move away from the shoe when the pincer jaws are opened.

105

22. In a machine of the class described, pincers each having a rigid and a movable jaw to engage an upper, means including pivoted cams for closing said jaws, a movable support for the pincers, and means for actuating said cams to first close the pincer jaws upon the upper and to thereafter move the pincers and their support to pull the upper.

115

23. In a machine of the class described, pincers each having a rigid jaw, a movable jaw, a rod connected with the movable jaw, yielding means acting on the rods to open the jaws, bell cranks connected with said rods, a movable pincer-support, pivotally-supported cams acting on said bell-cranks, and means for actuating said cams to first effect closure of the pincer jaws upon an up-

125

130

- per and to thereafter move said support and pincers to pull the upper.
24. In a machine of the class described, supporting rods, a bar connecting said rods, sleeves sliding on said rods, pincer shanks pivoted to said sleeves and having rigid jaws, movable jaws pivoted to said shanks, bell-cranks also pivoted to said sleeves, connections between said bell-cranks and movable jaws, cams pivoted to said rods and arranged to act on said bell-cranks, and means for actuating said cams to first effect closure of the pincer jaws and to thereafter move the pincers and their support to pull the upper.
25. In a machine of the class described, the combination with pincers arranged to engage an upper at the toe end and at the sides of a shoe, of sleeves to which said pincers are pivotally connected to provide adjustments for shoes of varying widths and lengths, and rods upon which said sleeves are supported for sliding movement.
26. In a machine of the class described, the combination with pincers arranged to engage an upper at the toe end and at the sides of a shoe, of supporting means for the pincers, pivotal connections between said parts to provide for adjustments of the pincers for shoes of varying widths and lengths, and means for securing the pincers in adjusted position.
27. In a machine of the class described, the combination with pincers arranged to engage an upper at the toe end and at the sides of a shoe, of supporting means for the pincers, pivotal connections between the side pincers and said means arranged to permit adjustments for variations in the width of shoes, a bar connecting said pincers and having means to secure said adjustments, a pivotal connection between the toe end pincer and said means arranged to permit adjustment for variations in the length of shoes, and means to effect said adjustment.
28. In a machine of the class described, the combination with a plurality of rods one of which constitutes a movable support, of a bar connecting said rods, sleeves mounted to slide on said rods, pincers having fixed and movable jaws and connected with said sleeves, said pincers being arranged to engage an upper at the toe end and at the sides of a shoe, springs arranged between said bar and sleeves, and means for causing the pincer jaws to seize the upper and for thereafter moving said rods and bar to yieldingly up-draw the upper.
29. In a machine of the class described, pincer mechanism comprising, in combination, a plurality of rods one of which constitutes a movable support for said mechanism, a bar connecting said rods, sleeves mounted to slide on said rods, pincers for engaging an upper connected with said sleeves, yielding means located between said bar and sleeves, and means for first closing the pincer jaws to seize the upper and for thereafter updrawing said movable rods to effect, through the pincers, a yielding pull of the upper.
30. In a machine of the class described, the combination with pincers, of a movable rod upon which said pincers are mounted, manually-operable means for first causing said pincers to engage a shoe upper and for thereafter retracting said rod to cause the pincers to pull the upper, and other means for causing a further movement of said rod to effect additional strain upon the upper.
31. In a machine of the class described, the combination with pincers, of a movable rod upon which said pincers are mounted, a yielding element between said pincers and rod, manually-operable means for first causing said pincers to engage a shoe upper and for thereafter retracting said rod to effect through the pincers a yielding strain upon the upper, and other means for causing a further movement of said rod to effect an additional strain upon the upper.
32. In a machine of the class described, the combination with pincers, of a movable rod upon which said pincers are mounted, a support for said rod, manual means for first closing the pincers' jaws upon a shoe upper and for thereafter retracting said rod to effect preliminary stretching of the upper, a latch carried by said support arranged to engage a fixed part and limit said stretching movement, and other manual means constructed to further retract said rod for additionally straining the upper and to then trip the latch for permitting rearward movement of said pincers when they release their grip upon the upper.
33. In a machine of the class described, the combination with pincers, of a movable rod upon which said pincers are mounted, a support for said rod, manual means for first closing the pincers' jaws upon a shoe upper and for thereafter retracting said rod to effect preliminary stretching of the upper, a latch carried by said support arranged to engage a fixed part of the frame and limit said stretching movement, other manual means constructed to further retract said rod for additionally straining the upper and to then trip said latch, and power-operated means for opening the pincers' jaws and thereby permitting the pincers to move away from the shoe.
34. In a machine of the class described, the combination with pincers for engaging a shoe upper, of a threaded rod upon which said pincers are mounted, yielding means between said pincers and rod, a nut for engaging the threads upon said rod, a pinion

connected with said nut, a toothed segment meshing with said pinion, and means for operating said segment to effect a yielding updraw of said pincers.

5 35. In a machine of the class described, the combination with pincers, of a rod upon which said pincers are mounted, manual means to cause said pincers to engage a shoe upper and to retract said rod for preliminary stretching the upper, a casing for supporting said rod, a latch on the casing arranged to engage a fixed part of the frame, and limit said stretching movement, a nut having threaded engagement with said rod,

10 15 a pinion connected with said nut, a toothed segment meshing with said pinion, connections including a yielding element between said latch and segment, and manual means for operating the segment to effect additional stretching of the upper and to thereafter trip said latch for permitting rearward movement of said pincers when they release their grip upon the upper.

15 20 25 30 35 40 45 50 55 60 65 70 75 80 85 90 95 100 105 110 115 120 125

36. In a machine of the class described, the combination with pincers, of manual means for causing the pincers to seize an upper at the fore part of a shoe and to strain the upper to a last, a toe-clasp, and power-operated means to close said clasp about the fore part of the shoe and to thereafter open said pincers.

37. In a machine of the class described, the combination with pincers located at the toe end and on each side of the fore part of a last, of manual means for first causing the pincer jaws to seize an upper on said last and for thereafter, by a continued movement, straining said upper to the last, means to apply additional strain to the upper, a toe clasp, and power-operated means to move said clasp into engagement with the shoe and wrap it about the toe end and to thereafter open said pincers and release the upper.

38. In a machine of the class described, the combination with pincers located at the toe end and on each side of the fore part of a shoe, of a manually-operable lever and connections to close the pincer jaws upon an upper and to thereafter move the pincers to updraw the upper, yielding means for opening said jaws, a toe clasp, and power-operated means for closing said clasp about the toe end of the shoe and for thereafter disconnecting said lever from the pincers to permit said yielding means to open the pincer jaws and release the upper.

39. In a machine of the class described, the combination with pincers located at the fore part of a shoe, of manual means to cause said pincers to seize the upper and updraw it, an upper pressing pad, a toe clasp, power-operated means constructed and arranged to move said pad and clasp into engagement with the shoe and there-

after to cause said pincers to release the upper, and means to move the pincers away from the shoe.

40. In a machine of the class described, the combination with pincers located to engage the upper at the fore part of a shoe, of manual means for causing said pincers to seize the upper and updraw it, a yielding device arranged to be put under tension during the updraw movement, a toe clasp, and power-operated means to move said clasp into engagement with the shoe and to thereafter cause said pincers to release the upper and permit said yielding device to move the pincers away from the shoe.

41. In a machine of the class described, the combination with pincers located to engage the upper at the fore part of a shoe, of manual means for causing said pincers to seize the upper and updraw it, a yielding device which is put under tension during the updraw movement, an upper pressing pad arranged to engage the top part of the shoe between the instep and the toe end, a toe clasp, and power-operated means to move said pad and clasp into engagement with the shoe and to thereafter cause said pincers to release the upper and permit said yielding device to move the pincers away from the shoe.

42. In a machine of the class described, the combination with pincers located to engage the upper at the fore part of a shoe, of manual means for causing said pincers to seize the upper and updraw it, a yielding device arranged to be put under tension during the updraw movement, a toe clasp, a toe tacker, and power-operated means to move said clasp into engagement with the shoe, to then effect release of the upper and permit said yielding device to move the pincers away from the shoe, and to thereafter move said tacker into operative relation to the shoe.

43. In a machine of the class described, the combination with pincers located to engage the upper at the fore part of a shoe, of manual means to cause said pincers to seize the upper and updraw it, a yielding device arranged to be put under tension during the updraw movement, a toe tacker, and power-operated means to effect release of the upper and permit said device to move the pincers away from the shoe, and to thereafter move the toe tacker into operative relation to the shoe.

44. In a machine of the class described, the combination with pincers located to engage the upper at the fore part of the shoe, of manual means to cause said pincers to seize the upper and updraw it, a yielding device arranged to be put under tension during the updraw movement, a toe tacker, and power-operated means to effect release of the

upper and permit said device to move the pincers away from the shoe, and to thereafter move the toe tacker into operative relation to the shoe and to effect operation 5 of said tacker.

45. In a machine of the class described, the combination with pulling-over means, of a toe clasp and a toe tacker which are located in positions removed from the shoe 10 during the operation of said pulling-over means, and power-operated means to wrap said toe clasp about the end of the shoe, to then effect release of the upper by the pulling-over means, and thereafter to move said 15 toe tacker into operative relation to the shoe.

46. In a machine of the class described, the combination with pulling-over means, of manual means to cause said pulling-over means to seize and pull a shoe upper, a toe 20 clasp and a toe tacker which normally occupy positions removed from the shoe, means to wrap said toe clasp about the toe end of the shoe, means to open the pincers and to move said pincers out of the path of 25 said toe tacker, and means to move said toe tacker up to the shoe and to operate the tacker for securing the upper in pulled-over position.

47. In a machine of the class described, 30 the combination with pincers and manually-operable means to cause said pincers to seize and preliminarily pull a shoe upper, a yielding element which is put under tension when the upper is being pulled, means for applying additional strain to the upper, a toe 35 clasp and a toe tacker which normally occupy positions removed from the shoe, and power-operated means constructed to wrap said toe clasp about the end of the shoe, to 40 open the pincers and thereby permit said yielding element to move said pincers away from the shoe, and to thereafter move said toe tacker up to the shoe and to operate the tacker for securing the pulled upper in 45 position.

48. In a machine of the class described, the combination with a shoe support, of 50 pulling-over means, a toe clasp and a toe tacker normally removed from the shoe on said support, and means for moving said parts up to the shoe to cause the clasp to embrace the toe end of the shoe and to operate the tacker for securing the upper in pulled-over position.

49. In a machine of the class described, 55 the combination with a shoe support constructed to hold a shoe in substantially upright position, of a toe clasp and a tacker normally positioned away from the shoe, 60 and mechanism for moving said parts toward the shoe to cause the clasp to embrace the toe end and to position the tacker close to the shoe, and thereafter to operate said tacker for driving tacks through the over-worked upper.

50. In a machine of the class described, the combination with a support for positioning a shoe slightly inclined to a vertical plane with its toe uppermost, of a guide removed from said support, a carrier movable 70 in said guide and carrying a toe end clasp and a tacker, and means to move said parts toward and from a shoe on said support.

51. In a machine of the class described, the combination with a shoe support, of a 75 guide, a carrier movable in said guide and supporting a toe end clasp and a tacker with capacity for movement of said parts relatively to each other, and means to move the carrier toward a shoe on the support to cause 80 the said clasp to first embrace the toe end of the shoe, to then position the tacker over the shoe, and thereafter to operate said tacker.

52. The combination with a shoe support, 85 of a toe end clasp supported for movements toward a shoe on said support and having a soft shoe-engaging face, pivoted arms for supporting said clasp, and yieldable means acting on said arms to hold the clasp open.

53. The combination with a shoe support, 90 of an end clasp for the shoe comprising a flexible band provided with a soft lining, pivotally supported levers having outer ends connected with said band and having also inwardly projecting portions, and a yielding 95 device acting upon said portions to hold the clasp open.

54. The combination with a shoe support, 100 of an end clasp for the shoe comprising a flexible band provided with a lining of soft material having teeth to frictionally engage 105 the shoe, pivotally supported arms connected at their outer ends to said band and having inwardly-extending projections, and a spring-pressed plunger engaging said projections for holding the clasp open.

55. The combination with a shoe support, 110 of an end clasp for the shoe comprising a flexible band provided with a soft lining, curved arms connected at their outer ends 115 to the extremities of said band and having inwardly projecting lugs, a carrier to which said arms are pivoted, a spring-pressed plunger moving in a recess in said carrier and arranged to act on said lugs and open 120 the clasp when said clasp is removed from engagement with a shoe, and means for actuating the carrier to cause the clasp to engage a shoe and close about the toe end thereof, thereby causing said lugs to force the 125 spring-pressed plunger back into said recess.

56. A machine of the class described having, in combination, tacking mechanism comprising a driver for use at the toe end of a shoe, and drivers for use at the sides of 125 the shoe supported for folding movements inward against the two sides and also angularly relative to the first-named movement to carry them over upon the edge of the shoe bottom, and means for moving said 130

drivers into and out of operative relation to the shoe.

57. A machine of the class described having, in combination, tacking mechanism comprising a driver for the toe end of the shoe, and drivers for the two sides of the shoe, all of said drivers being movable toward and from the shoe and also mounted to turn in over the edge of the innersole, the 10 two side drivers being additionally supported for folding movements inward against the sides of the shoe, and means for so moving said drivers and for imparting tack-driving movements thereto.

15 58. A machine of the class described having, in combination, tacking mechanism comprising a driver for the toe end of a shoe and drivers for the two sides of the shoe, means for supporting said drivers out of 20 operative relation to the shoe and in substantial alinement with each other, means for folding the side drivers in against the sides of the shoe and for turning said toe-end drivers and side drivers over upon the 25 edge of the shoe bottom to press the upper into the angle formed by the feather edge and lip of the innersole, means for supplying tacks beneath the drivers, and means to actuate said drivers.

30 59. A machine of the class described having, in combination, tacking mechanism comprising a driver for the toe end of a shoe and drivers for the two sides of the shoe, means for supporting said drivers out of 35 operative relation to the shoe, means for folding the side drivers in against the sides of the shoe and for turning all of said drivers over upon the edge of the shoe bottom and for pressing the upper into the 40 angle formed by the feather edge and lip of the innersole, tack-supplying means, a spring-pressed lever constructed to engage the drivers, and means to trip said lever when said drivers occupy the last-named positions.

60. In a machine of the class described, the combination with a shoe support, of a carrier mounted for movements toward and from said support, tack drivers on said 50 carrier, a spring-pressed lever pivoted to said carrier and having one arm constructed to engage said drivers and another arm connected with a fixed part of the machine, a latch to engage said lever, and means for 55 moving the carrier away from said support thereby moving said lever away from the drivers and permitting the latch to retain it in such position, and for moving the carrier toward the support to position the 60 drivers over a shoe, and thereafter to actuate said latch for tripping said lever to effect actuation of the tack drivers.

61. In a machine of the class described, the combination with a carrier supporting 65 tack-drivers, of a spring-pressed driver-

actuating lever fulcrumed to said carrier and having a shoulder, a latch to engage said shoulder and maintain an arm of the lever elevated above the drivers, a link connecting the other arm with the machine 70 frame, and mechanism including a rod to move the carrier away from a shoe thereby raising the lever and permitting the latch to retain said lever in such position, for moving the carrier toward a shoe and for 75 operating said latch for tripping the lever to thereby effect actuation of the drivers.

62. In a machine of the class described, the combination with a shoe support, of tacking mechanism movable relatively to 80 said support and including drivers and a spring-controlled actuating lever therefor, means for causing movement of said lever away from the drivers for storing power in its spring when said mechanism is moved 85 away from the support, a latch for retaining the lever in said position, and means for actuating the latch to trip the lever when said mechanism is moved toward said support.

63. In a machine of the class described, the combination with a shoe support, of tacking mechanism, and means to place said mechanism in condition for driving tacks while moving it away from said support, 95 and to effect the tack driving operation when said mechanism is moved into operative relation to a shoe on said support.

64. In a machine of the class described, the combination of a shoe support, tacking 100 mechanism including drivers supported for folding movements about the fore part of a shoe on said support, means for placing said mechanism in condition to drive tacks while moving it away from said support, and 105 means to effect the tack-driving operation when said mechanism is folded about the shoe.

65. A machine of the class described having, in combination, a shoe support, a guideway sustained in substantial alinement with a shoe on said support, a carrier movable in the guideway, tacking mechanism on said carrier including drivers arranged to be positioned about the fore part of the shoe, 110 a spring-pressed driver-actuating lever supported on the carrier, means to move the carrier away from the shoe and to store up power in said spring, means to supply tacks to said drivers, means to advance the 115 carrier toward the shoe, and for positioning the drivers in operative relation thereto, and means for tripping said lever to effect the tack-driving operation.

66. A machine of the class described having, in combination, means to support the parts of a shoe on a last in position to be assembled, having provision for movement to locate the shoe in a different position, power-operated means for driving tacks through 120 125 130

the assembled shoe materials while the shoe occupies the last-named position, means for pulling-over the shoe, and power-operated means to secure the shoe materials in pulled-over position.

67. A machine of the class described having, in combination, a shoe support having movement to carry a shoe from a position in which its parts are assembled on a last

0 to a different position, power-operated means for driving tacks through the assembled shoe parts while the shoe occupies the last-named position, means for pulling-over the shoe, a toe-tacker, and power-operated means for engaging the pulled upper about the toe end and above the ball of the shoe, for thereafter moving said tacker against the shoe and effecting the operation of said tacker to drive tacks through 15 the pulled upper, and finally to restore said tacker to a position removed from the shoe.

68. A machine of the class described having, in combination, a shoe support, power-operated means for driving a tack at the 20 rear end portion of a shoe on said support for securing the materials in assembled position, pulling-over means, a toe-clasp, and a toe-tacker, and power-operated means to move said clasp about the fore part of the 25 shoe, to then release the pulling-over means from engagement with the upper, to move the toe tacker against the shoe and operate said tacker, and finally to restore said toe clasp and toe tacker to the positions 30 which they originally occupied.

69. A machine of the class described having, in combination, a shoe support arranged to permit movement to carry a shoe from assembling position to pulling-over position, 35 pulling-over means to engage and pull the upper when the shoe occupies the last-named position, a toe clasp and a toe tacker which normally occupy positions removed from the shoe, means to move said clasp against the 40 shoe, means to disengage said pulling-over means from the upper and to move said means away from the shoe, and means to advance the toe tacker into engagement with the shoe and to operate said tacker.

70. A machine of the class described having, in combination, a shoe support arranged to permit movement to carry a shoe from assembling position to pulling-over position, 45 pulling-over means to engage and pull the upper when the shoe occupies the last-named position, a toe clasp and a toe tacker which normally occupy positions removed from the shoe, means to move said clasp against the shoe, means to disengage said pulling-over 50 means from the upper and to move said means away from the shoe, and means to advance the toe tacker into engagement with the shoe, to operate said tacker, and finally to restore said toe clasp and toe tacker to the 55 positions which they originally occupied.

71. The combination with a shoe support, of tack drivers on the support, springs for actuating said drivers, pawls pivoted to a movable member and arranged to engage said drivers, and means for moving said 70 member to cause the pawls to first lift the drivers and put their springs under tension and to thereafter trip the pawls and release said drivers.

72. The combination with a shoe support, 75 of tack-drivers on the support arranged to drive a tack through the materials at the back of the heel and another tack through the materials near the heel end of the sole, springs for actuating said drivers, a movable member, pawls pivoted to said member and arranged to engage said drivers, and means for moving said member to cause the pawls to first lift the drivers thereby putting their springs under tension and by a continued movement to trip said pawls to release said drivers and effect the driving of tacks through the shoe materials.

73. The combination with a shoe support, of tack-drivers on the support arranged for 90 driving two tacks substantially at right angles to each other, bars connected with said drivers and having lugs, springs connected with said bars, a movable member, pawls having angularly-related arms and 95 pivoted to said member, and means for moving said member to cause one arm of said pawls to engage the lugs and lift the drivers thereby putting said springs under tension and to thereafter cause the other 100 arms of said pawls to engage fixed projections and trip the pawls for releasing said drivers.

74. The combination with a shoe support, movable to carry a shoe from assembling position to pulling-over position, of tack 105 drivers carried by said support arranged to drive one tack through the materials at the back of the heel and another tack through the materials near the heel end of the sole, 110 and power-operated means to operate said drivers when the assembled shoe has been carried into pulling-over position.

75. In a machine of the class described, the combination with pincers having jaws to 115 seize a shoe upper, of yielding means for opening said jaws, means to close the jaws including a hand lever, a second lever provided with a toothed segment, a tooth carried by the hand lever and engaging said 120 segment, and power-operated means to move said tooth out of engagement with the segment to thereby permit said yielding means to open the pincer jaws and release the upper.

76. In a machine of the class described, the combination with pincers having jaws to seize a shoe upper, of yielding means for opening said jaws, manually-operable means for closing the jaws including a hand lever 125

fulcrumed to the machine frame, a second lever fulcrumed to said frame and having its arms formed as toothed segments, a third lever fulcrumed to said frame having one arm provided with teeth meshing with one of said segments and its other arm connected with the movable jaws of said pincers, a tooth supported from said hand lever and engaging the other segment, a cam pivotally supported from said frame, and means for causing the cam to force said tooth out of engagement with the segment and permit said yielding means to open the pincers' jaws and release the upper.

15 77. In a machine of the class described, the combination with pincers having fixed and movable jaws, of yielding means for opening said jaws, means for closing the jaws including a hand lever fulcrumed to the machine frame, a rack, a pawl carried by said lever and arranged to engage said rack, a pawl-controller connected with said pawl, a tooth pivotally supported from said lever and also connected with said controller, connections between said lever and the movable pincer jaws including a pivotally-supported member having a segment with which said tooth engages, a cam arranged to engage said tooth, and power-operated means to cause said cam to force the tooth out of said segment and thereby permit said yielding means to open the pincer jaws.

78. The combination with a movable support for holding a last in one position while the parts of a shoe are being assembled thereon, of a heel band, means to hold the band open while the last occupies said position and to close said band about the heel end of the last as said support is moved into a different position, and means to thereafter drive a fastening through the shoe materials.

79. The combination with a movable support for holding a last in one position while the parts of a shoe are being assembled thereon, of a heel band, means which is caused to close said band about the heel end of the last as said support is moved into a different position, and means for driving a tack through the shoe materials at the rear end of the last while said materials are held to the last by said heel band.

80. In a machine of the class described, the combination with fore-part tackers having rounded corners at their lower front edges, and supported for turning movements about axes extending substantially parallel with the plane of the shoe bottom, of means for causing the tackers to move about a shoe edge and to wipe the margin of the upper over upon the shoe bottom and into the angle formed by the feather edge and lip.

81. In a machine of the class described, the combination with fore-part tackers hav-

ing rounded corners at their lower front edges and angular flanges back of said corners and supported for turning movements about axes extending substantially parallel with the plane of the shoe bottom, of means for moving the tackers about a shoe edge to cause said corners to wipe the margin of the upper over upon the shoe bottom and into the angle formed by the feather edge and lip and to cause said angular flanges to press the upper against the end and sides of the shoe to form a well defined edge.

82. In a machine of the class described, the combination with fore-part tackers having rounded corners at their lower front edges, and supported for turning movements, of means for causing the tackers to move about a shoe edge and to wipe the margin of the upper over upon the shoe bottom and press it into the angle formed by the feather edge and lip, and means acting automatically to cause said tackers to drive tacks through the upper and innersole while the upper is pressed into said angle.

83. In a machine of the class described, the combination with fore-part tackers having rounded corners at their lower front edges and angular flanges back of said corners and supported for turning movements, of means for moving the tackers about a shoe edge to cause said corners to wipe the margin of the upper over upon the shoe bottom and press it into the angle formed by the feather edge and lip and to cause said angular flanges to press the upper against the end and sides of the shoe to form a well defined edge, and means acting automatically to cause said tackers to drive tacks through the upper and innersole while the upper is pressed into said angle.

84. The combination with a support for holding a last in one position while the parts of a shoe are being assembled thereon and movable into a different position, of means to clamp the shoe to the last as the support moves into the last-named position, and pulling-over means arranged for operation on the shoe while it occupies the last-named position.

85. The combination with a support for holding the parts of a shoe in position to be assembled on a last and movable to carry the shoe into a different position for the operation thereon of pulling-over means, of a clamp for holding the shoe parts to the last which is made operative as the support moves into the last-named position, means for driving a fastening to secure the shoe parts in assembled relation, and pulling-over means arranged for subsequent operation on the shoe.

86. The combination with a shoe support movable to carry a shoe from a position in which shoe parts are assembled on a last into a position for being pulled-over, of a

heel band, actuating means to cause it to close about the heel end of the shoe as the shoe moves into the last-named position, means for driving fastenings through the 5 assembled parts of the shoe, and pulling-over means.

87. The combination with means for supporting a shoe in one position while its parts are being assembled on a last, of a heel band, 10 and means independent of the shoe for closing said band about the heel end of the shoe as said support is moved into a different position.

88. The combination with means for supporting a shoe in one position while its parts are being assembled on a last, of a heel band or clasp, means operating automatically to close said band about the upper at the rear end portion of the last to hold the 20 shoe parts in assembled relation for the pulling-over operation as said support is moved into a different position, and pulling-over means arranged for operation on the shoe when the shoe is in the last-named position.

89. A shoemaking machine having, in combination, pulling-over means, and means for positioning a shoe in operative relation to said pulling-over means with the top of the forepart of the shoe facing the operator 30 and the toe end of the shoe pointing upward in a direction of non-intersection with a vertical plane extending between the shoe and the operator's working position, said shoe positioning means being movable between said pulling-over position and a different position in which the shoe is presented for a different operation to be performed thereon.

90. A shoemaking machine having, in combination, pulling-over means, and a shoe support arranged to present a shoe in operative relation to said pulling-over means with the top of the forepart of the shoe facing the operator and the toe end of the shoe 45 pointing upward toward the rear of the machine, said shoe support being movable about an axis extending laterally of the shoe to permit the shoe to be presented alternately in said pulling-over position and in 50 a different position for the performance of a different operation with respect to the shoe.

91. A shoemaking machine having, in combination, pulling-over means and means for positioning a shoe in operative relation to said pulling-over means with the top of the forepart of the shoe facing the operator and the toe end pointing upward toward the rear of the machine, said shoe positioning means being movable to permit the shoe to be presented alternately in said pulling-over position and in a different posture bottom upward for the performance of a different operation with respect to the shoe.

92. A shoemaking machine having, in

combination, pulling-over means and shoe positioning means relatively arranged to permit a shoe to be presented to said pulling-over means with its toe end pointing upward and with the top of the forepart of 70 the shoe facing the operator's working position, said shoe positioning means being movable about an axis extending laterally of the shoe to permit the shoe to be presented in said pulling-over position following its 75 presentation in a different posture bottom upward for the performance of a different operation with respect to the shoe.

93. A shoemaking machine having, in combination, pulling-over means and shoe 80 positioning means relatively arranged to permit a shoe to be presented to said pulling-over means with the top of the forepart of the shoe facing forwardly toward the operator's working position, said shoe positioning means being movable to permit the shoe to be presented in said pulling-over position following its presentation in a different position bottom upward with its toe end pointing toward the operator for the performance of a different operation with respect to the shoe.

94. A machine of the class described having, in combination, shoe positioning means arranged to occupy one position to 95 permit the parts of a shoe to be assembled on a last, said shoe positioning means being movable to present the shoe in a different position for a pulling-over operation with the top of the forepart facing the operator 100 and the shoe inclined with the toe end pointing upward toward the rear of the machine, and pulling-over means for operating on the shoe in said last named position.

95. A machine of the class described 105 having, in combination, means for positioning a shoe for an assembling operation with its bottom uppermost and its toe end pointing toward the operator, said shoe positioning means being movable about an axis extending laterally of the shoe to carry the shoe upward and present it with its toe end inclined toward the rear of the machine, and pulling-over means for operating on the 110 shoe in said last-named position.

96. A machine of the class described having, in combination, shoe positioning means arranged to occupy one position to permit the parts of a shoe to be assembled on a last, said shoe positioning means being 120 movable about an axis extending laterally of the shoe to present the shoe in a different posture for a pulling-over operation, and pulling-over means for operating on the shoe as thus presented.

97. A machine of the class described having, in combination, shoe positioning means movable to carry a shoe from assembling position to pulling-over position, and a sole rest into engagement with which 130

the shoe is carried in its movement to pulling-over position.

98. A machine of the class described having, in combination, shoe positioning means movable to carry a shoe from assembling position to pulling-over position, and a sole rest arranged to engage the shoe and arrest its movement to pulling-over position, said sole rest being adjustable to vary 10 the pulling-over position of the shoe.

99. A shoemaking machine having, in combination, means for positioning a shoe with the top of the forepart in view of the operator in his normal working position, means for gripping the upper of the shoe, manually operable means for moving said gripping means to pull the upper, and additional means arranged for operation subsequent to said first named manual means 20 for further moving said gripping means in substantially the same direction to pull the upper.

100. A shoemaking machine having, in combination, means for positioning a shoe 25 with the top of the forepart in view of the operator in his normal working position, means for gripping the upper of the shoe, manually operable means for moving said gripping means to pull the upper, and other 30 manually operable means for operating said gripping means to impart an additional pull to the upper.

101. A shoemaking machine having, in combination, means for positioning a shoe 35 with its toe end pointing upward and the top of the forepart facing the operator's working position, a pincer for engaging the upper of the shoe, manually operable means comprising a lever for moving said pincer initially to pull the upper, and additional 40 means comprising a manually operable lever movable in substantially the same direction as said first named lever for operating the pincer to impart an additional pull to the 45 upper.

102. A shoemaking machine having, in combination, a pincer for engaging an upper, means for operating said pincer to pull the upper, means for locking said pincer 50 operating means against retractive movement, and additional means for operating the pincer to impart a further pull to the upper while said first named means is locked.

103. A shoemaking machine having, in combination, a pincer for engaging an upper, means comprising a lever connected to the pincer for operating it to pull the upper, means for locking said lever at the end of 60 its upper pulling movement, and additional means comprising a second lever for further operating the pincer to pull the upper.

104. In a shoemaking machine, the combination with pincers arranged to engage an 65 upper at the sides of a shoe, of supporting

means upon which said pincers are pivoted to swing laterally of the shoe for varying the distance between them, and means extending between said side pincers, for determining their spaced relation and for holding 70 them against swinging movement in either direction laterally of the shoe.

105. A shoemaking machine having, in combination, a pincer for engaging an upper, a pincer rod on which said pincer is 75 mounted, manually operable means movable initially to cause the pincer to grip the upper and then to impart movement to said rod to cause the pincer to pull the upper, and additional manually operable means for 80 imparting further pincer operating movement to said rod.

106. A shoemaking machine having, in combination, a pincer for engaging an upper, manual means for operating said pincer 85 to pull the upper, a device for limiting the movement imparted to the pincer by said manual means, and additional means for imparting a further pulling movement to said pincer and for moving said device out of its 90 limiting position.

107. In a shoemaking machine, the combination with shoe positioning means, and means for preparing the shoe materials for a tacking operation, of tacking mechanism 95 movable toward and from a shoe positioned by said means, said mechanism comprising a tack driving member, a spring for operating said member, means operated by movement of the mechanism away from a shoe for putting said spring under tension, and means operated by movement of said mechanism toward a shoe for rendering said spring effective to operate the member.

108. A shoemaking machine having, in combination, upper gripping means, manually operative mechanism for operating said gripping means to pull the upper initially, a stop into engagement with which said mechanism is arranged to be normally 100 moved to limit the pull, and other means whereby an additional pulling movement of indeterminate extent may be imparted to said gripping means.

109. In a shoemaking machine, the combination with shoe positioning means, and means for preparing the shoe materials for a tacking operation, of tacking mechanism 115 movable toward and from a shoe positioned by said means, said mechanism comprising a tack driving member, a spring for operating said member, means operated by movement of the mechanism away from a shoe for putting said spring under tension, a latch for holding the spring under tension, and means 120 operated by movement of the mechanism toward a shoe for moving said latch to release the spring.

110. In a shoemaking machine, the combination with shoe positioning means and 130

- pulling-over means, of side tackers for fastening an upper in pulled-over position at the sides of a shoe, said tackers being mounted to swing about an axis extending laterally of the shoe to position them relatively to the plane of the shoe bottom and to move inwardly toward the sides of the shoe to position them relatively to the edge of the shoe bottom.
111. In a shoemaking machine, the combination with shoe positioning means and pulling-over means, of tacking mechanism comprising side tackers, said tackers being mounted for movement about an axis extending laterally of the shoe to position them relatively to the plane of the shoe bottom.
112. In a machine of the class described, the combination with means for pulling an upper into position at the toe of a last, of means for engaging the upper on the lateral surface of the last around the toe to retain the upper in position, said means comprising a flexible member conformable substantially to the shape of the lateral surface of the last and adapted to be wrapped around the toe of the last lengthwise of the edge of the shoe bottom.
113. In a machine of the class described, the combination with means for pulling an upper over a last, of a device for engaging and retaining upper materials in tensioned condition at the toe end of the last, said device being movable lengthwise of the shoe into engagement with the upper at the toe and comprising a flexible upper engaging member, and means for controlling the position of said member to cause it to be wrapped about the toe through the rearward movement of said device.
114. In a machine of the class described, the combination with means for pulling an upper over a last, of a device for engaging and retaining upper materials in tensioned condition at the toe of the last, said device being movable lengthwise of the shoe into engagement with the upper at the toe and comprising a flexible upper engaging member, and arms at opposite sides of the shoe to which the ends of said member are connected, said arms being yieldingly movable toward the shoe in response to the pull of said member in the rearward movement of said device.
115. In a machine of the class described, the combination with means for pulling an upper over a last, of a device for engaging and retaining upper materials in tensioned condition at the toe end of the last, said device being movable lengthwise of the shoe into engagement with the upper at the toe and comprising a flexible upper engaging member, arms at opposite sides of the shoe to which the ends of said member are secured, said arms being pivoted for movement toward or from the sides of the shoe, and spring means for retaining the arms normally at their outer limits of movement while permitting them to swing toward the shoe in response to the pull of said member in the rearward movement of the device.
116. In a shoemaking machine, the combination with upper pulling means, of means for engaging the upper peripherally around the toe of the shoe to hold it in tensioned condition, said upper engaging means comprising a flexible device conformable to the shape of the shoe, and means for wrapping said device around the toe by force applied lengthwise of the edge of the shoe bottom and holding it in operative relation to the shoe.
117. In a shoemaking machine, the combination with upper pulling means, of a flexible member arranged to extend continuously around the toe of the shoe to hold the upper in tensioned condition, and means for engaging said member at the sides of the shoe and pulling it lengthwise of the shoe into conforming and holding relation to the shoe.
118. In a shoemaking machine, the combination, with upper pulling means, of a flexible member for engaging the upper around the toe of the last to hold it in tensioned condition, arms for engaging said member at opposite sides of the shoe, and means for moving said arms rearwardly with respect to the shoe to wrap said member around the toe.
119. In a shoemaking machine, the combination with upper pulling means, of a flexible device arranged to extend continuously around the toe of the shoe lengthwise of the edge of the shoe bottom to hold the upper in tensioned condition, and means for applying said device in such relation to the shoe as to hold the upper with its marginal portion lying along the edge of the sole substantially at right angles to the plane of the shoe bottom and to permit the upper to be secured to the sole while the device remains in holding relation to the upper.
120. In a shoemaking machine, the combination with pincers and means for operating them to pull an upper, of a flexible end-embracing device arranged to be applied peripherally about the toe end of the shoe lengthwise of the edge of the shoe bottom to hold the upper in tensioned condition, and means for applying said device in such relation to the shoe as to permit the pincers to be released and the upper to be secured to the sole while the device remains in holding position.
121. In a shoemaking machine, an end embracing clasp conformable to the shapes of different shoes and comprising a plurality of substantially wedge shaped projections of yieldable material arranged to present their narrow edges for engagement.

with the shoe in substantially perpendicular relation to the plane of the shoe bottom.

122. In a shoemaking machine, an end embracing clasp conformable substantially to the shape of a shoe, said clasp comprising a flexible member provided with a plurality of projections of yieldable material arranged to present shoe engaging portions spaced laterally apart.
123. In a shoemaking machine, a flexible heel band constructed to be wrapped around the heel end of a shoe and to press the end portions of the counter of the shoe against the sides of the last, and means for pulling over the upper at the forepart of the shoe while the heel band is thus applied to the shoe.
124. In a shoemaking machine, the combination with shoe positioning means, of means for pulling over the upper of the shoe and for holding it under tension, a flexible clasp movable into engagement with the upper and constructed to be wrapped peripherally around the toe end of the shoe to retain the upper in tensioned condition and permit the upper pulling means to release the upper, and means for securing the upper in pulled-over position while it is thus held by the clasp.
125. In a shoemaking machine, the combination with shoe positioning means, of means for pulling over the upper of the shoe and for holding it under tension, means for engaging the upper peripherally around the toe end of the shoe to retain it in tensioned condition, power driving means, mechanism connected to said driving means for applying said upper engaging means to the shoe and for then holding said means in operative position with the machine at rest, and means operated by said power driving means when the machine is again started to secure the upper in pulled-over position.
126. In a shoemaking machine, the combination with shoe positioning means, of

means for pulling over the upper of the shoe and for holding it under tension, a clasp for engaging the upper peripherally around the toe of the shoe to retain it in tensioned condition, a support for engaging the shoe at the top of the forepart, power operated mechanism for moving said clasp and support into operative position and for maintaining them in such position with the machine at rest, and means operative when the machine is again started for securing the upper in pulled-over position.

127. In a shoemaking machine, the combination with shoe positioning means, of grippers and means for operating them to pull the upper of the shoe over the last, a flexible clasp constructed to be wrapped peripherally around the toe of the shoe to retain the upper in tensioned condition, power driven means for applying said clasp to the shoe and for causing the grippers to release the upper, and means for securing the upper in pulled-over position while it is held by said clasp.

128. In a shoemaking machine, the combination with shoe positioning means, of grippers and means for operating them to pull the upper of the shoe over the last, power driven means comprising a flexible clasp for engaging the upper peripherally around the toe of the shoe and for holding it in tensioned condition while the machine is at rest and the grippers are released from the upper, and means operative when the machine is again started to lay the margin of the upper over the bottom of the last and to fasten it.

In testimony whereof I have signed my name to this specification in the presence of two subscribing witnesses.

ANGELO PERRI.
